REMOVABLE AND REPLACEABLE HANDLE
FOR CROCHET NEEDLESErnest Herbert Suessman, East Hartford, Conn.,
assignor to C. J. Bates & Son, Chester, Conn.,
a partnership

Application December 31, 1949, Serial No. 136,267

9 Claims. (Cl. 66—118)

1

The invention relates in general to crocheting and relates more particularly to means designed and adapted to expedite and facilitate the manipulation of crochet needles or hooks while adding to the comfort and convenience of the crochet worker.

A principal object of the invention is the provision of a removable and replaceable handle for crochet needles adapted to accommodate practically any conventional type of crochet needle, while affording convenient gripping-means for the needle and its immediate withdrawal when desired.

Another object of the invention is to provide a removable handle for crochet needles, of a pleasing configuration, and having means to accommodate the crochet needle to the most convenient position while preventing orientation of the hook during the process of crocheting.

Another object of the invention is to provide a gripping crochet-holder suitably recessed to accommodate a crochet needle to a predetermined position and having convenient gripping-fingers to maintain the needle in the best operating position.

Another object of the invention is to provide a replaceable handle for crochet needles that will serve as a convenient receptacle or sheath for the crochet needle when not in use, in addition to its normal function of facilitating crochet work when employed.

A further object is to provide, as an article of manufacture, a combination gripping-handle and sheath for crochet needles.

Other objects and advantages will appear to those skilled in the art from the following, considered in conjunction with the accompanying drawings.

The invention is adapted for use with conventional type crochet needles, and is designed to afford a more convenient gripping control over the crochet needle and provides a comparatively small, pleasingly configured receptacle for the crochet needle when not in use.

In the accompanying drawings, in which certain modes of carrying out the present invention are shown for illustrative purposes:

Fig. 1 is a perspective view of one embodiment of the invention as operatively applied to a crochet needle;

Fig. 2 is a plan view of the device with a crochet needle arranged in normal operating position;

Fig. 3 is a side elevational view of the arrangement shown in Fig. 2;

Fig. 4 is an enlarged transverse sectional view, taken on line 4—4 of Fig. 3;

2

Fig. 5 is a view similar to Fig. 4 taken on line 5—5 of Fig. 3;

Fig. 6 is a detached plan view of a conventional type crochet needle, as used in the arrangement shown in Fig. 1;

Fig. 7 is a side elevational view of the needle depicted in Fig. 6;

Fig. 8 is a perspective view of the removable handle, with portions broken away for clarity of illustration;

Fig. 9 is a view similar to Fig. 2 and showing a modified form of the invention;

Fig. 10 is a side elevational view, similar to Fig. 3, of the embodiment shown in Fig. 9;

Fig. 11 is an enlarged transverse, fragmentary, sectional view taken on line 11—11 of Fig. 10;

Fig. 12 is a view similar to Fig. 11 taken on line 12—12 of Fig. 10; and

Fig. 13 is a perspective view of the modified form of replaceable handle.

The showing of Figs. 1 to 8

In the drawings depicting the first form of the invention and wherein similar characters of reference indicate corresponding parts in the several views of the present form of invention, the numeral 20 designates generally a crochet needle or hook of conventional type, and having the customary hook 21, a cylindrical shank or body-portion 22, and a finger-gripping flat 23 of customary flared configuration, as viewed in Fig. 6, and adapted to serve in combination with the holder of the present invention, as an abutment to restrict the location of the needle within the holder to a desired position.

The crochet holder of this invention, designated generally at 24, comprises a body-portion 25 of a somewhat oval configuration, as viewed in cross section (Fig. 5), and tapering from the right-hand side, as seen in Fig. 2, divergingly toward and to approximately the dotted line 26 (indicating the bottom of the bifurcation) where it merges with a pair of integrally-formed, resilient gripping-fingers or lips 27, 28 that may be said to form a mouth portion of the holder.

As shown in Fig. 3, it will be noted that each of the fingers 27, 28 is formed with an outer concavity, as at 29, for a purpose that will appear hereinafter. The body-portion 25 of the handle 24 is formed with a passageway or bore 30, of diameter suitable to snugly receive the cylindrical shank 22 of the crochet needle 20. As best shown in Figs. 2 and 3, it will be observed that when the bore 30 accommodates the shank of the needle, the enlarged flat portion 23 of the hook upon its initial entrance into the bore 30 to a point slightly beyond the bottom of the

bifurcation (dotted line 26 of Fig. 2) will begin to wedgingly engage the adjacent inner surface of the said bore and thus serve with the latter as an abutment to prevent further movement of the shank of the hook in a direction from left to right, as seen in Figs. 2 and 3.

Further inspection of Fig. 3 will disclose that the gripping-fingers 27, 28 on their inner opposed surfaces have a convex configuration, as at 31. These inwardly-bulging or convex portions of the gripping-fingers serve to clampingly engage the opposite flattened sides of the flat 23 of the hook 20 and prevent its turning while providing a comfortable resting and clasping position for the fingers of the crochet worker.

In manufacture, the device is preferably formed or composed of a single portion of material such as methylmethacrylate, cellulose-acetate, urea-formaldehyde, phenol-formaldehyde, etc. It is to be understood that the material selected in this form of the invention is preferably resilient or elastic, in order to clampingly accommodate the flat 23 of the crochet needle. The clamping pressure, of course, may be supplemented by the fingers of the crochet worker, and in all cases it will be understood that the crochet needle, by its clamping retention to the holder, is prevented against turning or undesired longitudinal movement during crochet work. The actual configuration disclosed is designed to be pleasing to the eye, and, at the same time, to adapt itself conveniently to the best manipulating position of the average crochet worker's hand.

The functioning of the device and its mode of use has been, in large measure, indicated above by the foregoing description. The crochet needle is introduced with the cylindrical body-portion of the needle, initially thrust through the gripping-fingers 27, 28, and thence through the elongated bore 30 of the body-portion of the handle to a point where the flat 23 will commence to wedgingly abut against the beginning of the said bore 30, as described above and as indicated in Figs. 2 and 3. The flat 23, of necessity, will practically self-orient itself into a position where the opposite sides of the said flat are in contact with the convex inner opposed surfaces 31 of the gripping-fingers 27, 28. The device is now ready for application to crocheting work.

The showing of Figs. 9 to 13 inclusive

In the modified form, a slightly different design and construction is employed. In the figures depicting this form, the numeral 40 designates generally a holder conforming to the precepts of the invention. The holder 40, which has a tapering configuration, comprises two comparatively-thin flat strips of flexible material 41, 42 such as leather, rubberized composition, fabric, etc., placed in opposed juxtaposition and having their outer longitudinal edges bound together approximately two-thirds of their length by a pair of binder-strips 43, 44 of suitable metal or alloy. This construction affords flexible gripping-fingers or flaps at the forward end of the holder, and a restricted opening at the narrow end of the taper through which the butt end of the needle is protruded.

The binder-strips 43, 44 are U-shaped when viewed in cross section (Fig. 12), and of a longitudinally-tapering configuration, as seen in plan (Fig. 9), each strip having a pair of opposed longitudinally-extending flanges, as at 45, pressed into clamping engagement with the outer adjacent pair of aligned edges of the opposed flexible

strips 41, 42, thereby anchoring the latter in the position shown.

The shape and disposition of the flexible strips 41, 42 provide a comparatively-narrow tapering and elongated passageway or bore, as at 46, serving to clampingly accommodate the shank 22 of a crochet needle and permit its partial egress from the right-hand extremity of the holder. By reason of the flexible nature of the strips 40, 41, in the present instance the flat enlarged portion 23 of the crochet needle, it will be found, will not be stopped abruptly, as in the case of the positive abutment-means afforded in the first form of the invention, but, by reason of the taper, will move inwardly with increasing resistance to a predetermined limiting or stop position. However, the instant form lends itself to a somewhat increased latitude in the actual dispositioning of the needle relatively to the holder, and in all cases, the needle may be moved to a position which the worker finds most convenient to his individual taste. Here, again, the holder serves the purpose not only to expedite and facilitate the crocheting, but also as a sheath or receptacle to store the crochet needle when not in use.

It will be evident that in the present, as in the first, form of the invention, the cost of manufacture of the item is approximately nominal, and that it is particularly adapted for quantity production and distribution to the trade.

The invention may be carried out in other specific ways than those herein set forth without departing from the spirit and essential characteristics of the invention, and the present embodiments are, therefore, to be considered in all respects as illustrative and not restrictive, and all changes coming within the meaning and equivalency range of the appended claims are intended to be embraced therein.

I claim:

1. A removable handle for use with a crochet needle having in its shank an intermediate flattened portion, said handle comprising a body-portion having a bore extending longitudinally thereof, and two opposed flat resilient clamping-portions at one end of said body-portion, said clamping-portions having confronting convexly-configured surfaces adapted to engage the opposite surfaces, respectively of the flattened portion of the needle-shank.

2. A combination operating-handle and sheath for use with a crochet needle, comprising a pair of comparatively-thin flat strips arranged in opposed juxtaposition, means so binding superposed lengths including adjacent ends of the outer edges of said flexible strips to each other that the corresponding strip lengths define between the bound edges thereof a substantially-flat tapering through-passage adapted to accommodate the shank of a crochet needle, the remaining lengths of said strips forming opposed flexible lips which are wider than the passage-forming strip lengths and serve as a handle with which to grip the shank of a crochet needle.

3. A combination operating-handle and sheath for use with a crochet needle, comprising a pair of flexible tapered strips arranged in opposed juxtaposition, channel-elements straddling and clamping superposed lengths including the narrower spaced ends of the opposite edges, respectively, of said flexible strips so that the corresponding strip lengths define between the clamped edges thereof a substantially-flat tapering through-passage adapted to accommodate the shank of a crochet needle, the remaining

lengths of said strips forming opposed flexible lips serving as a handle with which to grip the shank of a crochet needle.

4. A combination operating-handle and sheath for use with a crochet needle, comprising a body-portion of tapering configuration, a pair of resilient fingers formed integrally with and extending longitudinally from the body-portion, said fingers having outer concave gripping-surfaces and inner bulging convex surfaces, said convex surfaces being effective to receive and clamping-ly engage a flattened portion on a conventional crochet needle, and said body-portion having a longitudinally-extending bore therein communicating with a gap between said elastic fingers.

5. An operating-handle for a crochet needle having a hook at one end of its shank, said handle comprising a sheath having a tubular body-portion adapted axially to receive a length of the needle-shank remote from the hook thereon with a sliding fit, and an end-portion providing opposite lips flexible into engagement with, and being of substantially greater width than, the needle-shank.

6. An operating-handle for a crochet needle having a flat in an intermediate length of its shank, said handle comprising a sheath having a tubular portion adapted axially to receive at least a length of the needle-shank on one side of the flat therein with a sliding fit, and an end-portion providing opposite lips flexible into engagement with, and being of substantially greater width than, the flat in the needle-shank.

7. An operating-handle for a crochet needle having a flat in an intermediate length of its substantially-cylindrical shank, said handle comprising a sheath having a tubular portion adapted axially to receive at least a length of the needle-shank on one side of the flat therein with a sliding fit, and an end-portion providing opposite flat lips flexible into engagement with,

and being of substantially-greater width than, the flat in the needle-shank.

8. An operating-handle for a crochet needle having a flat in an intermediate length of its shank, said handle comprising a sheath having a tubular portion adapted axially to receive at least a length of the needle-shank on one side of the flat therein with a sliding fit, and a mouth-portion continuous with said tubular portion and providing separate opposite lips flexible into engagement with, and being of substantially-greater width than, the flat in the shank, said tubular portion being of less width than said mouth-portion.

9. An operating-handle for a crochet needle having a flat in an intermediate length of its shank, said handle comprising a sheath having a tubular portion adapted axially to receive at least a length of the needle-shank on one side of the flat therein with a sliding fit, and a mouth-portion integral and continuous with said tubular portion and providing separate opposite flat lips normally flexing into engagement with, and being of substantially-greater width than, the flat in the shank.
